UNITED STATES PATENT OFFICE.

PAUL MAUSER, OF OBERNDORF-ON-THE-NECKAR, GERMANY.

SMALL-ARM.

1,008,552.

Specification of Letters Patent. Patented Nov. 14, 1911.

Application filed January 27, 1911. Serial No. 604,937.

To all whom it may concern:

Be it known that I, PAUL MAUSER, privy commercial councilor, a subject of the King of Wurttemberg, residing at Oberndorf-on-the Neckar, in the Kingdom of Wurttemberg, Germany, have invented certain new and useful Improvements in Small-Arms, of which the following is a full, clear, and exact description.

10 This invention relates to a modification of an invention for which I obtained Letters Patent No. 943949 and which refers to a recoil loader with fixed barrel and locking levers, which latter are actuated by a sliding cam plate and move inward and outward after the manner of arms.

20 The invention has for its object to facilitate the withdrawal of the breech block during single loading without the necessity for retaining the sliding cam plate in its 25 unlocking position. For this purpose there is provided in connection with the sliding cam plate a spring catch which can be put into and out of engagement and which after being moved into its locking position engages with the sliding cam plate during its forward movement and holds it fast until the breech is opened and has again been 30 closed, whereupon after the catch has been moved back the sliding cam plate springs back into its locking position.

35 The accompanying drawings illustrate by way of example a constructional form of a recoil loader in accordance with this invention wherein—

Figure 1 shows the parts when the catch is thrown out of engagement, that is to say, in position to admit of the automatic operation of the weapon. Fig. 2 is an underside 40 view of the breech cover with the catch, as in Fig. 1, thrown out of engagement and Fig. 3 shows in longitudinal section the position of the parts with the catch in the locking position.

45 The general arrangement of the breech system is the same as in the specification of aforesaid patent.

50 The locking of the breech block *k* is effected by the locking levers *b* which are actuated by the sliding cam plate *a* and the pins *b¹* of which are so acted upon by the slots *a¹* of the sliding cam plate that, when the latter is in its rearward position, the front portions of the slots retain the fore 55 ends of the locking levers *b* in contact with the end of the breech block, while when the

slide is in its forward position the levers *b* are, by the rear portion of the slots *a¹*, moved outward into the unlocking position. The sliding cam plate *a* is arranged to move 60 freely in the breech cover in such manner as to be independent of a separate actuating-device or of other parts of the breech and it is provided with gripping projections *a⁴* extending laterally outward.

65 Now in accordance with the present improvement there is arranged, in connection with the sliding cam plate *a* and preferably also in the breech cover, a spring locking arm *w* which can be put into and out of 70 engagement and which, when in the locking position, engages with its front notched end *w¹* behind an inner projection *a⁵* of the 75 sliding cam plate *a* and by this means prevents the rearward movement of said cam plate under the pressure of its spring. The forward and backward movement of the spring locking arm is effected by means of a controlling lever *u* which is rotatably mounted on the upper side of the cover and 80 which in its two extreme positions of engagement and disengagement can be retained by spring engagement with corresponding notches of a guide groove *u¹*. The pivot *v* of this adjusting lever *u* passes inward through the cover and is provided with a projection *v¹* which, when the lever 85 is turned into the locking position, passes over the spring locking arm *w* and by this means keeps it pressed down. When in this 90 position the end *w¹* of the arm *w* must, when the sliding cam plate *a* is pressed forward, fall into the locking position behind the projection *a⁵* so that the sliding cam plate is held in the unlocking position against the 95 action of its spring *s*. The breech block can now be drawn backward without difficulty and can also again be pushed forward without the necessity, as has hitherto been the case, of holding the sliding cam plate by 100 hand in the unlocking position. When the breech block is again moved forward and controlling lever *u* is turned into the position of disengagement, the sliding cam plate is released and, by means of its spring, 105 which up to this time has been under compression, is brought back into the locking position.

What I claim as my invention and desire to secure by Letters Patent is:

110 1. In an automatic breech loading firearm, the combination with a breech bolt,

locking levers therefor, and a cam plate adapted to move said levers into and out of locking position, of means adapted to permanently retain said cam plate in position to maintain said locking levers in unlock position.

2. In an automatic breech loading fire-arm, the combination with a breech bolt, locking levers therefor, and a cam plate adapted to move said levers into and out of locking position, of means adapted to permanently retain said cam plate in position to maintain said locking levers in unlock position, and means for moving said retaining means into and out of position to retain said cam plate.

3. In an automatic breech loading fire-arm, the combination with a breech bolt, locking levers therefor, and a sliding cam-plate adapted to move said levers into and out of locking position, of a spring catch adapted to be moved into and out of position to permanently retain said sliding cam plate in position to maintain said locking levers in unlock position, whereby said breech bolt may be moved to open and close the breech.

4. In an automatic breech loading fire-arm, the combination with a breech bolt, locking levers therefor, and a sliding cam-plate adapted to move said levers into and

out of locking position, of a spring catch adapted to be moved into and out of position to permanently retain said sliding cam plate in position to maintain said locking levers in unlock position, whereby said breech bolt may be moved to open and close the breech, and means for moving said spring catch into and out of position to retain said cam plate.

5. In an automatic breech loading fire-arm, the combination with a breech bolt, locking levers therefor, and a sliding cam-plate adapted to move said levers into and out of locking position, of a spring catch adapted to be moved into and out of position to permanently retain said sliding cam plate in position to maintain said locking levers in unlock position, whereby said breech bolt may be moved to open and close the breech, and a lever having a projection thereon adapted to engage said spring catch for moving said spring catch into position to retain said cam-plate.

In witness whereof, I have hereunto signed my name in the presence of two subscribing witnesses.

PAUL MAUSER.
